ATTORNEY

UNITED STATES PATENT OFFICE

2,514,748

WASTE SPRAY COLLECTOR

Albert Di Stefano, Philadelphia, Pa.

Application February 5, 1946, Serial No. 645,506

4 Claims. (Cl. 299—140)

1

This invention relates generally to the class of liquid diffusing and spraying apparatus and is directed primarily to improvements in paint spraying machines.

In the use of paint sprayers or paint guns where the paint or lacquer or other coating material is projected in a fine spray from a nozzle under air pressure, a considerable amount of vapor or mist is developed around the surface against which the coating material is projected so that the user of the machine is exposed to the necessity of breathing in such said mist or vapor to his detriment.

Various types of apparatus have been devised for collecting the mist or vapor developed in this manner but such devices are usually designed as separate units from the spray gun, to be connected or attached thereto for use and disconnected therefrom when the spraying operation is completed and such attachments are clumsy and awkward to use and materially interfere with the ease of operation of the spray gun.

A principal object of the present invention, in view of the foregoing, is to provide an apparatus or attachment for a paint spray gun which functions to draw off the vapor or mist developed around the area against which the coating material is projected and to extract or filter out the coating material from the air and discharge the cleansed air to the rear of the gun.

Another and more specific object is to provide a spray or paint gun attachment in which use is made of a portion of the air delivered to the gun, for setting up a reverse flow of air through a filtering medium whereby the mist or vapor which develops around the surface being coated, is drawn into the device and removed from the air, the air being discharged rearwardly from the gun and the extracted coating substance being collected in a receptacle provided for the purpose.

Another object of the invention is to provide a modified paint spray gun with a vapor or mist collector wherein rearwardly directed air jets are employed which receive air from the supply which operates the gun, to set up in and through a chamber enclosing the paint spray, a reverse flow of air and discharge the same rearwardly from the gun, such reverse flow of air being drawn through a filtering material so that the paint or other coating material which it may carry is effectively removed therefrom, thus maintaining the air around the user of the spray gun, clean and free of any paint particles.

A still further object of the invention is to provide a spray gun structure having an air cleansing

2

means associated therewith, with a novel control valve mechanism which is entirely under the control of a single trigger element for the supplying of the necessary air under pressure to the spray nozzle and to the jet from which air is ejected in the reverse direction to the spray nozzle and within a funnel unit to cause the spray laden air to be drawn through a filtering element.

Still another object of the invention is to provide in a spray gun of the character above stated, a novel valve mechanism under the control of a single operating trigger, for delivering air to the two oppositely directed jets or nozzles, with means operated by a single finger control for varying the sizes of the valve apertures through which the air passes, upon actuation of the trigger, to the spray nozzle and to the air jets.

Other objects and advantages of the present invention will become apparent as the description of the same proceeds and the invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in side elevation of a spray gun equipped with a waste spray collector constructed in accordance with the present invention, parts of the spray collector being in section.

Figure 2 is a vertical longitudinal section, on an enlarged scale, taken longitudinally of the structure, through the head portion of the gun and the adjacent parts of the spray collection bells and the air discharge tube or funnel.

Figure 3 is a transverse sectional view taken substantially on the line 3—3 of Figure 1.

Figure 4 is a transverse sectional view taken substantially on the line 4—4 of Figure 1.

Figure 5 is a view partly in horizontal section and partly in top plan of the casting which forms the body or frame of the paint gun.

Figure 6 is a sectional view taken substantially on the line 6—6 of Figure 2 illustrating the positions of the reciprocating air admission valve and the rotary valve when the air ports to the air jets and to the spray nozzle are open.

Figure 7 is a sectional view corresponding to Figure 6 but showing the positions of the valves

when the air ports to the air jets are closed and the port to the spray nozzle is open.

Figure 8 is a vertical sectional view through the casting, taken substantially upon the line 8-8 of Figure 5.

Referring now more particularly to the drawings the reference character C generally designates the casting which forms the body or frame of the paint gun, the detailed features of which will be hereinafter more fully set forth, while the reference character A generally designates the leak-proof fitting which couples the inlet nozzle 10 with the paint receptacle or bucket B, which receptacle is maintained firmly in position through the medium of the hanger frame D and the clamp mechanism E. These last mentioned parts A, B, D and E are of standard well-known construction and form no part of the present invention, therefore, it is believed that a more detailed description and illustration of the same are not necessary.

The casting C comprises the hand grip portion 11 through which an air passageway 12 is formed, the lower end of such passageway being suitably screw-threaded to receive the coupling nipple 13, by means of which an air supply hose, not shown, is connected with the gun to supply air from a suitable source.

The front side of the hand grip 11 is provided with the upwardly opening socket 13' across the bottom or lower end of which a pivot pin 14 extends, to mount a portion of the trigger mechanism as hereinafter described.

At the upper end of the hand grip, the casting is formed to provide a head which is generally designated H and which is formed in the front and rear portions 15 and 16 respectively which are separated by the chamber 17, the upper end of which is closed by the removable cover plate 18 while the lower end is open and is directed downwardly toward the upper part of the socket 13'.

Between the upper end of the hand grip 11 and the rear part 16 of the head, is formed the tapered rotary valve seat 19, the rear end of which is interiorly threaded as indicated at 20 while the forward end leads through the short straight cylindrical portion 21 to the threaded opening 22 in which is fitted a valve stem guide and packing assembly 23.

The straight forward end portion of the rotary valve seat has formed longitudinally thereof the key rib 24 for the purpose hereinafter set forth.

The upper end of the air passage 12 through the handle opens into the rotary valve space 25, through the inlet port 26 and in advance of this port 26 or toward the smaller end of the seat which is formed by the wall of the area 25, is an outlet port 27 leading to the spray nozzle, hereinafter described, and a second outlet port 28 which leads to the jet passage 29 which feeds the three air jet nozzles 30 which form a part of the rear portion 16 of the head. These jets 30 are preferably three in number and are formed or grouped around a guide passage 31, the outer end portion of which is screw-threaded as indicated at 32.

As stated the air jet nozzles 30 are directed along lines paralleling the axis of the space 25 and extending perpendicular to the hand grip and the passage 31 likewise extends parallel to the discharge line for the nozzles or lengthwise of the head.

The forward portion 15 of the head has formed therethrough an air passage 33 which is con-

nected, by means of the side passage 34 which is disposed at one side of the head, with the port 27. Paralleling this passage 33 and extending upwardly through the part 15 of the head is a guide passage 35 in which is secured a sleeve 36 through which extends a needle valve 37, the head 38 of which is accessible from the underside of the casting head for the opening or closing of the valve.

In the upper part of the part 15 there is formed the chamber 39, the outer end portion of which is threaded as indicated at 40 and this chamber has the central opening 41 leading rearwardly therefrom into the enlarged threaded portion 42 which is axially aligned with the passage 31.

At the front side of the casting head portion 15 there is secured the paint spray head 43, by means of the threaded stem 43' which engages the threaded portion 40 of bore 39. This head 43 has the tapered forward end portion 43'' through which is formed the paint discharge opening 44.

In the casting head portion 15 there are formed the two annular channels or passages 45 and 46 and the paint spray head 43 has formed therein the forwardly leading passages 45' and 46' which, at their rear ends communicate respectively with the annular passages or channels 45 and 46. The paint spray head, as shown, covers and closes the forward sides of these channels 45 and 46 thus making them into closed annular compartments.

In the casting head portion 15 there are formed the two axially directed passages 33' and 33'', the first of which leads directly from the passage 33 to the annular air channel 45, while the second one leads to the annular air channel 46. As shown these passages 33' and 33'' are parallel and in relatively close relation and the wall between them is provided with the tapered opening 33''' which forms a seat for the point of the needle valve 37, such valve extending across the passage 33' so as to have its pointed end introduced into the tapered opening 33''' to control the flow of air from the passage 33' to the passage 33''.

The tapered portion 43'' and the outlet aperture 44 of the head 43 form the paint spray nozzle and the air passage 45' leading from the channel 45 discharges at its forward end across the outer side of the tapered portion 43''.

Overlying and positioned concentrically with the paint nozzle is the detachable air nozzle 47 which is formed to provide the conical inner passage chamber 47' which leads to the outlet 47'' which encircles the reduced end of the portion 43'' of the paint nozzle and is spaced therefrom to provide a circular opening through which air issues around the paint stream.

A portion of the rear end of the air nozzle 47 is counterbored so that when the rear end of the air nozzle comes into position against the rear part of the paint nozzle there is formed the annular chamber 48 into which the air passage 46' leads. The conical interior of the air nozzle, in advance of the counterbored portion which forms the chamber 48, co-acts with the tapered forward end portion of the paint nozzle to form the circular air chamber 48' which is in communication with the passage 45' and from which the air issues through the port 47''.

The chamber 48' may be identified as the fanning air chamber as it is from this chamber that the air flows through the passages 48'' formed through the two horns 48'', to be discharged from the inwardly directed jet ports 49 obliquely across the path of the paint issuing from the port 44. These jet ports constitute the well-

known fanning or width control jets which under certain conditions apply opposing streams of air against the paint stream so as to flatten out the paint stream in the form of a fan or brush. When the fanning jets are shut off by means of the needle valve 37 the paint and air spray will issue as a cone.

The air nozzle 47 is secured in place by the fastening collar or securing band 50 which threads onto the forward part of the portion 15 of the casting head. This securing band 50 is exteriorly tapered for the purpose hereinafter described.

Slidably mounted in the opening 41 which is aligned with the paint receiving chamber 39, is a reciprocable valve stem 51, the tip or point 52 of which enters the aperture 44 of the spray head to close the latter under the action of a spring 53 which is enclosed in the guide passage 31 and is operatively coupled with the valve stem as shown to normally urge the stem forwardly to closed position.

In the opposite or rear end of the passage 34 is threaded a tension screw 54 which tapers off rearwardly to a point as shown for streamlined action in the air blast which flows rearwardly therearound from the jet nozzles 30.

As shown the paint control valve stem 51 extends across the upper part of the chamber 17 and is enclosed in and connected with a guide sleeve 55, the forward end of which forms a shoulder for engagement by the hereinafter described trigger lever.

The part 45 of the casting head has a paint passage 56 formed therein which, at its lower end, is in communication with the tube 60 while at its upper end it opens through the port 56 into the paint chamber 39 of the spray head. Threaded into the outer end of the rotary valve chamber 25 is a bearing adjusting nut 57. This nut maintains in position a tapered rotary valve which is generally designated 58 and which may be defined as an adjusting valve. The rotary valve 58 is hollow, having formed therein the circular chamber 59 which is of reduced diameter through substantially half its length at the inner or smaller end of the valve whereby there is formed between the two portions of different diameters a tapered valve seat 60.

Secured in the outer end of the tapered valve 58 is the head 61 which has formed as an integral part thereof, the stem 62 which passes through the center of the adjusting nut 57 and has secured to its outer end the control lever 63.

The interior diameter of the nut 57 is greater than the outside diameter of the head 61 and there is located in the space between these two bodies the spring 64 which constantly urges the valve 58 inwardly against the seat 60.

Within the smaller end of the tapered valve 58 is snugly fitted the cylindrical slide valve 65. This valve has the tapered valve head 66 which is adapted to position on the seat 60 to shut off communication between the inner and outer portions of the chamber 59. The outer portion of the chamber 58 in the tapered valve 58, has a circumferentially directed port 67 which is at all times in communication with the air port 26 leading from the passage 12 in the hand grip.

Adjacent to the inner or smaller end of the tapered valve 58 there are formed the two outlet ports 68 and 69, the port 68 being arranged for registry with the port 28 leading to the jets 30 while the port 69 is arranged for registry with the port 27 leading to the spray head 43 by way

of the passages 33 and 34 and the chamber 46. As shown the port 67 is upon the opposite side of the seat 60 from the two outlet ports 68 and 69.

The slide valve 65 has a recess or pocket 70 formed in the forward end or the end opposite from the head 66 and extending on the axial center of this valve body is a stem guide passage 71 while adjacent to this passage is an air by-pass passage 72 which at its forward end opens into the pocket 70 while its rear or back end opens into a recess 73, the encircling wall of which is tapered to form a valve seat 74. In addition the slide valve body has the obliquely directed chamber 75 formed therein around the passages 71 and 72. This chamber at one end opens through the wall of the valve body in close proximity to the head 66, as indicated at 76, while it is divided at its opposite end to form the two ports 77 and 78 which are located adjacent to the forward end of the valve. When the slide valve is retracted or moved to open position the port 76 registers with the port 67 of the tapered valve while the ports 77 and 78 register respectively with the ports 68 and 69 of the tapered valve 58, when the tapered valve is in open or partly open position. This tapered valve 58 may be turned to a position where its port 68 will be out of registry with the air jet port 28, in which case, of course, the port 71 of the slide valve will not register with the port 28 when the slide valve is retracted or moved to open position, as illustrated in Figure 7. However, the air outlet port 69 of the tapered valve is of sufficient circumferential extent that even when the tapered valve is turned to close off the flow of air to the jets 30 communication will still be maintained between the supply ports 26 and 67 and the nozzle head port 27.

Extending through the stem guide passage 71 of the slide valve is a portion of the stem 79 of an auxiliary valve 80. The auxiliary valve 80 is in the form of a poppet valve and is adapted to position on the seat 74 of the slide valve while the opposite end portion of the stem extends into the guide 81 which is formed axially in the head 61. A spring 82 has one end connected with the head 61 and engages against the rearward side of the valve 80 to force the latter onto its seat.

The forward end of the valve stem 79 extends into the pocket 70 and is contacted by a trigger stem 83 which extends through the guide and packing assembly 23, into the lower part of the space 17 of the casting head. The packing of the assembly 23 prevents escape of air from pocket 70, around stem 83.

The numeral 84 designates the auxiliary trigger which, as shown, is of substantial length and has its lower end extended downwardly into the socket 13 where it is pivotally secured by the pivot pin 14. This auxiliary trigger extends across the outer or forward end of the trigger stem 83 and its upper end extends to the upper part of the space 17 and is slotted or bifurcated as indicated at 85 to receive or straddle the paint valve stem 51. This bifurcated upper end of the auxiliary trigger is normally spaced forwardly of the shoulder forming guide 55 in which the stem 51 is secured. It will thus be seen that a slight amount of oscillation is permitted the auxiliary trigger 84 before the upper end of the trigger will engage the sliding guide member 55 and cause the stem 51 to be retracted for the discharge of paint through the nozzle.

Pivoted in the forward part of the space 17 between the side walls of the casting head, at 86, is the trigger 87.

As shown the trigger 87 extends downwardly in front of the auxiliary trigger 84 and terminates in a plane above the top of the socket portion 13 in which the auxiliary trigger is pivotally disposed. The rear side of the trigger 87 is suitably formed for rocking or camming engagement against the auxiliary trigger 84 so that when the trigger 87 is pulled rearwardly the desired rocking movement will be transmitted to the auxiliary trigger 84 to cause movement of the several valve parts.

The paint spray collector of the present invention consists of three main parts which are, the filter unit or filter bell generally designated 88, the intermediate portion or bell and funnel connector generally designated 89, and the rear part or air funnel which is generally designated 90.

The filter bell is, as its name implies, a body of substantially bell-like form, comprising the spaced inner and outer walls 91 and 92 respectively which are maintained in the desired spaced coaxial relation by the spacer bars or rods 93 and 94.

The outer shell or wall 91 of the bell terminates in the annular band 95 at its smaller end while at its larger end it is provided with an aperture 96 which leads through the threaded nipple 97 to which is detachably connected the drainage receptacle 98.

The inner shell terminates at its small end in the collar 99 which is press fitted to and encircles the tapered locking band or ring 50.

Disposed concentrically within the inner shell 92 is the funnel shaped spray baffle 100, into the smaller end of which the spray nozzle is directed on its axial center. The smaller end of this baffle is held in place by tight engagement around the air jet horns 48", so that an air passage is provided between the horns through which air may flow from between the baffle and shell 92. The baffle and inner shell are coupled together by rods 93 and 94, as shown in Figure 1.

It will be noted that in addition to the fact that the forward end of the baffle 100 is inwardly of the forward or larger end of the shell 92 as illustrated, such forward end of the shell 92 is also placed inwardly with respect to the forward end of the larger and outer shell 91. This arrangement allows for the ample flow of the paint laden air into the space between the two shells or walls of the filter bell.

In the rear or smaller end of the filter bell there is placed, between the two spaced screen walls 102, a filtering material 103 in the form preferably of cotton or cotton waste. This filter unit in effect forms a band or collar around the rear end of the inner shell 92 and partitions the space between the inner and outer shells.

Filling the space between the inner and outer shells 91 and 92 from the forward one of the screens 102, to the forward end of the shell, is a coarser filtering material 104 which is formed preferably of a mass consisting of many short lengths of relatively thin aluminum ribbon, which have been twisted, corrugated or otherwise deformed and which are placed side by side, forming a built up layer from one end of the bell to the other. These are vertically positioned to facilitate drainage.

The connector 89 comprises two substantially semi-circular bodies of substantial length to cover and enclose the head portion of the casting. The

two portions of this connector are designated 105 and each portion is provided along its lower longitudinal edge with a flange 106 through which suitable securing elements 107 are passed into the adjacent side of the head which is located between the two sections.

The longitudinal top edge of one section 105 is formed to provide the slot 108 and the opposing longitudinal edge of the other section forms a tongue 109 which extends into this slot.

The forward end of the connector 89 receives the annular rear end portion 95 of the filter bell wall 91 and the two parts of the connector at the front end are drawn tightly together around the band 95 by a bolt and nut 110 which is passed through the opposed apertured ears 111. Similar ears 112 are formed at the rear ends of the parts 105 so that this rear end portion of the connector may be drawn together or constricted around the inserted smaller end of the air funnel 90.

The air funnel 90 is of tapered form, being larger at its rear end and the forward end of the funnel is finished in the annular band portion 113 which is received in the connector.

The larger and rear end of the funnel 90 is pressed to form the encircling groove 114 for the attachment to the funnel, if desired, of a fabric duct, not shown.

As shown when the spray collector is in position upon the casting head a substantial air space will be formed through the connector around the head and the air jet nozzles 30 will be enclosed and directed rearwardly through the air funnel, the outlets of the nozzles being disposed to form a circle around the axial center of the funnel.

In the operation of the invention when the valve trigger 87 is pressed, movement is imparted to the auxiliary trigger 84 as previously stated and this in turn puts pressure against the shaft 83 and actuates the auxiliary valve 80. While any desired range of movement for the auxiliary valve 80 and for the auxiliary trigger 84, may be provided, it is preferred that the auxiliary valve 80 be lifted from its seat when it has shifted approximately $1/64$ th of an inch or, rather, when the auxiliary stem 83 has been shifted to this extent by the auxiliary trigger 84. This movement of the auxiliary valve 80 will, of course, be against the pressure of the air filling the rear part of the chamber 59 of the tapered valve. When the auxiliary valve 80 has been lifted from its seat the air under pressure will flow through the by-pass passage 72 into the socket 70 in the forward end of the slide valve. This transfer of the air under pressure to the opposite end of the slide valve, balances the pressure upon the two ends of such valve, thereby permitting it to be shifted from its seat 60 with a minimum of effort.

Further oscillatory movement of the auxiliary trigger 84 causes the enlarged inner end 83' of the stem 83 to press against the forward end of the slide valve and this will be shifted approximately an $1/8$ th of an inch to unseat the head of the slide valve before the bifurcated upper end of the auxiliary trigger 84 is brought into operative engagement with and starts to shift the paint valve stem 51.

This lead of air flow over the paint flow is necessary for the proper formation of the spray and to have the necessary air current moving through the separator between the bell walls 91 and 92 and through the funnel 90. In this manner the waste or paint mist which does not adhere to the surface being coated, will be immediately

picked up and carried off through the filter structure.

The slide valve 65 is, as previously stated, of cylindrical form and the underface of the head is ground so as to engage tightly upon the seat 60. Thus when the slide valve is closed leakage of the air past the same is prevented.

When the slide valve is shifted or opened, the air under pressure moves through the oblique chamber or passage 75, the air flowing through the outlet 77 into the passage 29 and to the jets 30 and through the other outlet 78 to the port 71 and to the spray nozzle.

While the slide valve 65 is moved it gives proportional and progressive flow of air to both the air jets and the nozzle. This permits air flow increase to follow up the paint flow increase proportionally. When a heavier spray is desired, more air is needed to provide it and therefore an increase in air flow to draw off the extra paint, is necessary.

When the trigger pressure is released the spring 82 operates to re-seat the auxiliary valve 80 and the slide valve 65. When this occurs the air pressure on the supply side of the slide valve 65 augments the action of the spring 82 to maintain the two valves tightly on their seats. This arrangement allows for the use of a spring of relatively light weight or only of sufficient strength to move the valve parts into place.

In order to prevent the slide valve from turning on its axis and thereby changing the positions of the ports relative to the ports of the tapered valve 58 with which it cooperates, the forward end portion of the slide valve is provided with a key groove 115 which receives the key rib 24 formed in the wall of the straight portion of the chamber or passage 25 in which the tapered valve is positioned.

The tapered valve 58 is held tight on its seat by the spring 64. This valve adjusts the quantity of air which is permitted to flow when the slide valve is actuated and the adjustment is made through the medium of the lever 68, by turning the tapered valve 58 so that the port 68 thereof may be in full registry with the port 28 leading to the air passage 29 and to the jets 30 or the air leading to the jets may be cut down or completely shut off as desired. The air will be proportionately graduated for the port 27 leading to the nozzle but will not be completely shut off to the paint spray air nozzle port 47 even when the port 28 leading to the jets is completely closed.

When certain types of work are to be performed the air flow to the rearwardly directed air jets 30 may be cut off and when this is done the waste collector 98 will not be used. For example, when the fanning adjustment valve 38 is open, air will be discharged from the jets 49 to flatten out the paint spray stream, in which case the spray may be applied by moving the device in the same manner as a brush is moved. In this case the collector unit would not be used.

A particular advantage of the present waste paint spray collector lies in the fact that paint may be sprayed onto areas lying close to or adjacent to other areas which are not to be painted, without requiring the application of masking material to such other areas. The device is also of value in painting business places or other places where the usual activities cannot be interrupted, because in the use of the spray collector no paint will be scattered beyond the mouth of the bell to be dissipated into the air. In business establishments or other places where activities must con-

tinue, the usual process has been to use brushes for painting, since the ordinary paint spray guns cannot be used because of the scattering of the paint spray. With the present device the spray gun can be used and no spray will be scattered and, therefore, a job may be completed easily and quickly without interrupting the usual activities of the establishment.

It will be readily apparent that the device may be used with or without the collection head or bell and when the use of the collection bell is not required, the connector 89 and the funnel 90 may be removed.

When the air collector bell is used to draw the waste spray back through the filtering material it will be seen that when air is discharged from the jets 30, there will be set up a movement of air through the filtering mass in a filter bell before the paint spray is discharged due to the fact that when the trigger 67 is first depressed air will be permitted to flow to the jets 30 before the forked upper end 85 of the auxiliary trigger opens the valve 51 which permits the paint to escape from the outlet aperture 44 of the paint nozzle. Thus when the spray comes into operation any of the spray which does not adhere to the surface but is dispersed into the air, will be immediately drawn back by the air currents through the cleansing and filtering mass so that the operator of the gun will not be forced to breath in air laden with the paint as is the case in the use of the ordinary spraying device. The paint which is extracted from the air by the filtering mass will collect in the lower forward part of the outer shell of the filter bell, from which it will drain off into the collector receptacle 98 and the paint free air will be discharged rearwardly through the funnel 90.

From the foregoing it will be readily apparent that there is provided in the present invention a spray gun and waste paint collector which may be operated with ease and which will function to effectively remove any paint mist or spray which rebounds from the surface being coated. At the same time the device is so constructed and arranged that it may be operated without fatigue and it does not require the connection of any auxiliary suction apparatus which would make the handling of the spray gun awkward and cumbersome.

In connection with the detachable fabric air duct it is to be pointed out that when using fast drying paints the air duct will be used but the filtering mass is removed.

I claim:

1. In a spray gun having a spray head and a spray nozzle forming a part thereof, a waste spray collector comprising a bell-like unit having a large end and a small end and having spaced inner and outer walls, the space between said walls being open at both ends of the unit and the space within the inner wall being open at the larger end of the unit, means at the smaller end of the inner wall portion of the unit for securing such inner wall portion to the spray nozzle for the direction of spray through the unit on the axial center thereof, a relatively long air conductor connected with the smaller end of the unit at the rear end of the outer wall portion, the air conductor having a portion of said spray head therein and being open at the end remote from the unit, and means forming a part of the spray head extending within said conductor for discharging air under pressure through the air conductor away from said unit.

2. A waste spray collector for a spray gun, as stated in claim 1, in which the said means for directing air through the air conductor comprises an air jet forming a part of the spray head, with means for delivering air to said jet in advance of the discharge of spray from the spray nozzle. 5

3. A waste spray collector for a spray gun, as stated in claim 1, with means between the inner and outer walls of said unit for extracting paint from air passing between said walls, and means 10 for draining off and collecting the paint extracted from the air passing between the unit walls.

4. A waste spray collector for a spray gun, as stated in claim 1, with a relatively coarse metallic filter mass filling the space between the inner and outer walls of the unit, a relatively tightly packed body of fine filtering material forming a partition between said inner and outer walls at the smaller 15 end of the unit, and a drain and collector means connected with the outer wall of the unit at the 20 lower part thereof.

ALBERT DI STEFANO.
